BEVERAGE MIXER AND DISPENSER

William V. Johnson, Washington, D. C.

Application October 10, 1941, Serial No. 414,512

2 Claims. (Cl. 225—26)

This invention relates to a beverage mixer and dispenser, and it is an object of the invention to provide a device of this kind whereby may be readily admixed the ingredients required to produce a desired beverage.

It is also an object of the invention to provide a device of this kind which not only provides for the desired mixing of the various materials, but is also provided with means whereby such materials may be thoroughly and effectively agitated and mixed before being dispensed.

An additional object of the invention is to provide a device of this kind provided with means whereby certain of the materials may be refrigerated, together with means whereby carbonated or other gaseous liquids may be readily discharged within a storage compartment with substantially no loss of the gaseous charge.

The invention consists in the details of construction and in the combination and arrangement of the several parts of my improved beverage mixer and dispenser whereby certain important advantages are attained, as will be hereinafter more fully set forth.

In order that my invention may be the better understood, I will now proceed to describe the same with reference to the accompanying drawing, wherein:

Figure 1 is a view in elevation, with a portion broken away, of a beverage mixer and dispenser constructed in accordance with an embodiment of my invention;

Figure 2 is a view in top plan of the device as illustrated in Figure 1, with certain of the parts omitted; and

Figure 3 is an enlarged transverse vertical sectional view taken substantially on the line 3—3 of Figure 1, with certain of the parts in elevation.

As disclosed in the accompanying drawing, R denotes a main receptacle of desired dimensions and configuration and which, as herein disclosed, has its side and back walls 1 of a hollow type to provide a dead air space for the purpose of heat insulation, although it is to be stated that if preferred the interior of these walls 1 may have placed therein a suitable filler of heat insulating material.

In the present embodiment of my invention, the front wall 2 of the receptacle R is of a single thickness and this front wall 2 also constitutes a front wall for each of the relatively large containers C within the receptacle R, the bottom wall 3 for the receptacle R also constituting a bottom wall for each of the containers C. Each of the containers C is also of a height substantially

equal to the height of the receptacle R and the upper open end of each of the containers C is closed by a removable cover or lid 4 of any particular type.

- 5 In the present embodiment of my invention, the containers C are two in number and arranged side by side and separated one from the other by a common inner end or side wall 5. These containers C are of such dimensions as to allow 10 within the receptacle R the end and rear spaces 6 to receive cracked ice or other suitable refrigerating medium, as indicated at 7 in Figure 3. A supply of any suitable liquid may be placed within each of the containers C as, for example, gingerale, carbonated soda, etc. In filling each 15 of the containers C, and particularly when the liquid is of a gaseous nature, the cover or lid 4 for each of the containers C is provided with a central opening 8 in which is tightly fitted an end portion of a plug 9. This plug 9 may be of rubber or other compressible material, or of such other material which can be employed to advantage. This plug 9 is of a length to allow the neck portion of a bottle of carbonated or gaseous liquid to be engaged thereover so that the liquid 20 within the bottle or container may be readily discharged within the container C through an elongated tube 10. This tube 10 has one end portion disposed lengthwise through the plug 9 and end portion of a plug 9. This plug 9 may be of rubber or other compressible material, or of such other material which can be employed to advantage. This plug 9 is of a length to allow the neck portion of a bottle of carbonated or gaseous liquid to be engaged thereover so that the liquid 25 within the bottle or container may be readily discharged within the container C through an elongated tube 10. This tube 10 has one end portion disposed lengthwise through the plug 9 and is of a length to have its lower or opposite extremity terminate closely adjacent to the bottom of the container C. Slidably disposed through the plug 9 is a second elongated tube 11. Before a bottle or other holder is engaged with the plug 30 9 the second tube 11 is pulled upwardly so that the same will extend within such bottle or holder to a point closely adjacent the bottom of the inverted bottle or holder. This will allow the air within the container C being filled, to pass up 35 through the inverted bottle or container engaged with the plug 9 and thereby assure the proper flow of the liquid from within the bottle or other holder out through the tube 10 into the container C to be filled.
- 40 Normally, the tube 11 is substantially housed within its container C, as illustrated in Figure 3, and disposed over the outer portion of the plug 9 to protect the same as well as the adjacent portion of the tubes 10 and 11 is a cap 12. As illustrated in the accompanying drawing, 45 this cap 12 threads upon an upstanding collar 14 defining the opening 8.
- 45 Positioned in advance of the receptacle R, at the upper portion thereof and carried by the 50 front wall 2, are the smaller receptacles S here-

in disclosed as five in number, although I do not wish to be understood as limiting myself in this respect, as these containers S may be of such number as may be preferred.

These containers S are adapted to hold a supply of different liquids to be mixed with the liquid drawn from either of the containers C. The liquids in the containers S may be liquors such as rye whisky, Scotch whisky, gin, and the like, or may be different wines, flavors, or such other liquids as may be preferred.

The front wall 2 of the receptacle R is common to all of the containers S and constitutes the rear wall of such containers S. The bottom wall 15 of each of the containers S is oppositely inclined or beveled downwardly, and at the low point thereof has depending therefrom a discharge pipe or conduit 16 leading to and delivering within an elongated mixing receptacle 17. As herein disclosed, this receptacle 17 is cylindrical in form and has its opposite end closed by the removable heads 18 whereby ready access may be had within the receptacle 17 for cleansing or other purposes. As illustrated in Figure 1, the receptacle 17 is inwardly and downwardly inclined from its opposite ends, and at its low point is formed to provide a well 19. In communication with and depending from this well 19 is a discharge spout 20, the discharge through the spout 20 being under control of a conventional type of valve 21.

Each of the pipes or conduits 16 has the flow therethrough under control of a conventional valve 22, and each of the receptacles R is in communication with the mixing receptacle 17 through a pipe or conduit 23. The flow through each of these pipes or conduits 23 is under control of a conventional valve 24. Each of the containers S is adapted to have its upper open end closed by a removable cover or lid 25, and the open top of the space 6 is also preferably closed by a removable cover or lid 26, as illustrated in Figure 3.

With the use of my improved device, when it is desired to mix a required beverage, a valve 24 is adjusted into open position, as determined by the required liquid, and there is also opened one of the valves 22, as determined by the desired liquid in one of the containers S. After the required amounts of such materials have been delivered within the mixing receptacle 17, the valves 22 and 24 are closed.

The materials delivered within the mixing receptacle 17 will flow down toward the well 19 and be discharged out through the spout 20 upon opening of the valve 21. It is of importance to provide means to assure effective mixing of the materials within the receptacle 17 before being discharged out through the pipe 20. As herein disclosed, extending within the well 19 is the lower end portion of an elongated rod or shaft 27 which extends upwardly and freely through a suitably positioned opening 28 provided in one of the walls 29 separating adjacent

containers S. This rod or shaft 27 is of a length to extend slightly above the containers S and the upper or extended end portion of this rod or shaft 27 carries a relatively heavy wheel 30 of a diameter to be readily grasped between the digits of a hand to cause a spinning action to be imparted to the rod or shaft 27. The lower end portion of the rod 27 within the well 19 carries a bladed agitator 31 whereby the liquids or materials within the receptacle 17 are thoroughly agitated and mixed as a result of the spinning action effected through the wheel 30.

The various receptacles and containers as herein comprised may be formed of any desired material but it is essential that the portion of the wall of the mixing receptacle 17 adjacent to and above the well 19 be transparent so that visual access may be had within the receptacle 17 to determine the amount of liquids delivered within said receptacle and also to observe the mixing of such materials. In the present embodiment of the invention, the front wall of the receptacle 17, immediately above the well 19, is provided with a window opening 32 tightly closed by the transparent plate 33.

From the foregoing description it is thought to be obvious that a beverage mixer and dispenser constructed in accordance with my invention is particularly well adapted for use by reason of the convenience and facility with which it may be assembled and operated.

I claim:

1. An apparatus of the class described including a receptacle, liquid holding containers within the receptacle, a cylindrical shaped mixing receptacle extending across and carried by the first receptacle below the containers, said mixing receptacle being inwardly and downwardly inclined from its opposite ends, a valve controlled communication between each of the containers and the mixing receptacle, a series of aligned containers carried by the first receptacle above the mixing receptacle, each of said second containers having valve controlled communication with the mixing receptacle, and a valve controlled discharge for the mixing receptacle.

2. An apparatus of the class described including a receptacle, liquid holding containers within the receptacle, a cylindrical shaped mixing receptacle extending across and carried by the first receptacle below the containers, said mixing receptacle being inwardly and downwardly inclined from its opposite ends, a valved communication between each of the containers and the mixing receptacle, a series of aligned containers carried by the first receptacle above the mixing receptacle, each of said second containers having valve controlled communication with the mixing receptacle, a valve controlled discharge for the mixing receptacle, and removable heads for closing the opposite ends of the mixing receptacle.

WILLIAM V. JOHNSON.
